UNITED STATES PATENT OFFICE.

LEONARD M. DAVIS, OF KNOXVILLE, TENNESSEE.

FLUE CLEANER.

1,408,934.

Specification of Letters Patent.

Patented Mar. 7, 1922.

Application filed November 2, 1920. Serial No. 421,296.

To all whom it may concern:

Be it known that I, LEONARD M. DAVIS, a citizen of the United States, residing at Knoxville, in the county of Knox and State 5 of Tennessee, have invented a new and useful Improvement in Flue Cleaners, of which the following is a specification, reference being had to the accompanying drawing.

My improvement relates particularly to 10 flue cleaners operated by the use of steam in such manner as to induce a powerful draft of air through the flue to be cleaned.

The object of the invention is to provide a 15 structure which is strong and efficient in operation and which can be made to a large extent out of stock materials, whereby the manufacture is simplified and cheapened. The invention is equally adapted to cleaning one tube at a time or to cleaning two tubes 20 simultaneously.

In the accompanying drawings.

Fig. 1 is a side elevation of an apparatus embodying my improvement, parts being broken away;

25 Fig. 2 is a longitudinal upright section of the left hand part of the same apparatus;

Fig. 3 is a continuation of the section shown by Fig. 2;

30 Fig. 4 is a sectional view of a structure to be used for cleaning two tubes.

Referring to said drawings, A is the discharge end of one of the tubes of a horizontal tubular boiler. Usually there is a smoke stack above the discharge end of such a boiler, and my invention contemplates moving the accumulations of soot and ashes out 35 of the discharge end of such a tube and upward through the smoke stack. A structure embodying one form of my im-

40 provement is shown in its entirety by Fig. 1, excepting that portions of the body are broken away to shorten the drawing. B is a tubular, cast metal head curved so as to form a mouth, B¹, having a horizontal axis

45 and to form a discharge nozzle, B², which is directed upward on an upright axis. The mouth has a lip, B³, which is converging toward the mouth axis so as to adapt it to extend partially into and bear against the

50 end of a boiler flue. Said lip is supported by and integral with the flaring part, B⁴. By the combination of the lip and the flaring part in the manner shown the slanting exterior of the lip is attained while the inter-

55 rior diameter of the lower part of the head is kept within limits and this part of the

head is kept in form for easy molding. From the part, B⁴, the structure is of approximately uniform diameter until the upright part of the structure is reached. Thence there is 60 a gradual contraction to the upper end of the structure, whereby the discharge end of the nozzle is made smaller than the interior diameter of the mouth at the lip, B³. In the outer wall of the curved part of the structure, approximately in line with the axis of the mouth, B¹, is formed a pipe connection, B⁵. The external part of this connection is on a horizontal axis and is internally screw-threaded and adapted to receive the exterior 65 screw-threaded end of a pipe, C. The member, B⁵, is turned upward from the horizontal to the upright and the upright part is tapered to form an upward-directed nozzle, B⁶.

70 The member, B⁵, and its nozzle, B⁶, and the lip, B³, and flaring part, B⁴, are parts of the head, B, said members or parts being cast integral with the other parts of the head. The nozzle, B⁶, extends into the interior of 75 the head, B, far enough to discharge upward into the middle part of the nozzle, B².

The right hand end of the pipe, C, is screw-threaded into one end of the branch coupling, C¹. Said coupling has the branch, 80 C², into which is threaded the upper end of a pipe, C³. Over the lower end of said pipe is drawn a flexible tube, D, which is to be connected with a source of steam supply or similar expansive medium. The left hand end 85 of a pipe, C⁴, is screw-threaded into the right hand end of the coupling, C¹. A tubular handle, E, of wood or other non-heat-conducting material surrounds the pipe, C⁴, at any desired point.

90 The socket, E⁴, of a handle, E³, surrounds the right hand or outer end of the pipe, C⁴, and is secured to said pipe by means of a set bolt, E⁵. Said handle may be turned after loosening the set bolt. Thus the handle may 95 be adjusted to meet the needs of any operator. The handle, E, may be shifted endwise on the pipe, C⁴, to vary the distance between that handle and the handle, E³, to meet the needs of different operators. The handle, E, 100 may be secured in the desired position by means of pins, E¹, set in apertures, E², formed in the pipe, C⁴. The left hand or inner end of the pipe, C⁴, is closed by means of a plug, G.

105 The operation is as follows:

One end of the flexible pipe, D, is at-

tached to the branch, C³, and the other end of said pipe is joined to a source of supply of steam or other elastic fluid under compression. Then the apparatus is placed horizontally into alignment with a flue to be cleaned, the mouth, B¹, of the head, B, being pressed against the discharge end of the flue, so that discharge from that end of the flue can take place only through the body, 10 B. Steam now passes through the flexible pipe, D, the pipe, C³, the coupling member, C⁴, the pipe, C, the connecting member, B⁵, and its nozzle, B⁶, and upward through the nozzle, B², of the head, B. The upward 15 pressure of the steam is sufficient to drive before it all the air and other gaseous constituents. By this means a partial vacuum is created in the head, B, and air rushes forward through the flue, A, into said head. 20 This displacement of air and consequent partial creation of a vacuum in the head, B, proceeds continuously, and consequently there is a continuous flow of air and combustion products through the flue, A. The 25 stream of air and combustion products thus created has such velocity as to cause the dislodging and forward movement of soot and ashes from the interior of the flue, A, such movement being upward through the head, B. The blast created by the steam escaping from the nozzle, B², accelerates the normal draft in the smoke stack and consequently all the soot and ashes are carried upward 30 through the smoke stack. 35 As already stated, the head, B, and its lip, B³, and the connecting member, B⁵, with its smaller nozzle, B⁶, constitutes an integral or one-piece casting requiring no machining whatever excepting to interiorly thread the 40 outer end of the connecting member, B⁵. The pipes, C, C³ and C⁴, may be cut from any stock piping such as is used for steam or water distribution. The pipe, C⁴, need be threaded only at its left hand end and be 45 provided with the apertures, E², for the pins, E¹. The plug, G, is placed into the left hand or inner end of the pipe, C⁴, to exclude steam from said pipe.

The construction so far described is that 50 used when the device is to be used for cleaning one tube at a time; but when it is desired to clean or blow out two tubes simultaneously, I add to the structure shown in Figs. 1, 2 and 3 the necessary elements to 55 permit the cleaning of two tubes at once, this additional mechanism being shown in Fig. 4. In said Fig. 4 the head, B, instead of being made of the exact shape shown in Figs. 1 and 2, may have the member, B⁵, formed with a second pipe connection B⁷ shown in Fig. 4.

To this pipe connection B⁷ is connected 60 a pipe H on which is a valve F, this valve preferably having a crank arm, F¹, and a 65 spring, F², the latter normally holding the

valve closed. To the crank arm, F¹, is connected a wire F³, supported in guides C⁵ which extends out in proximity to the handle E so that the operator having hold of the handle may, by slipping a finger through 70 the ring F⁴ on the end of the wire F³, pull said wire F³ and open the valve F for a purpose to be hereinafter described. To the lower end of the pipe H is connected by 75 means of an elbow, a horizontal pipe I at right angles to the pipe H, the latter forming a support for a casting or head J having a flaring mouth J¹ substantially identical with the mouth B¹ of Figs. 1 and 2. The pipe I is extended through the casting J and is 80 shaped to form a nozzle I¹ so as to permit steam to be injected through the casting whenever the valve F is opened by pulling on the wire F³. In the operation of this 85 form of my invention, the operator places 90 the apparatus shown in Fig. 4 so that the two mouths B¹ and J¹ are in contact with two companion tubes, as the tubes T¹ and T² shown in Fig. 4. Steam being admitted to the 95 apparatus through a pipe D identical with the pipe D shown in Fig. 1, the valve F being closed, the action of the apparatus is identical with that shown in Fig. 1. As soon, however, as a draft has been created upwardly 100 in the nozzle B² of Fig. 4 so that the suction cleaning action is beginning to take place, the operator may then pull upon the wire F³ to open the valve F when steam will also pass downward through the pipe H and out 105 through the nozzle I¹ so that it will be injected into the tube T². The further operation of the device now has a combined action 110 the steam causing a suction through the upper tube T¹ while the steam is positively forced through the other tube T² thus 115 effectively cleaning the two tubes simultaneously.

I claim as my invention,

1. In a portable structure of the nature described, the combination of a member having a mouth adapted to be placed on the end of one tube and having an upward directed nozzle to cause suction to clean said tube and an auxiliary nozzle device adapted to be placed on the end of a second tube to force steam therethrough, and operator-controlled means for delivering steam to said nozzles, substantially as described.

2. In a portable structure of the nature described, the combination of two members adapted to be placed on the ends of two boiler tubes closing the tubes, one of said members having an upward-directed nozzle directed to provide suction from one of said tubes and the other member having a nozzle 120 to drive steam through the other tube, and operator-controlled means for delivering steam to said nozzles, substantially as described.

3. In a portable structure of the nature de- 130

scribed, the combination of two members adapted to be placed on the ends of two boiler tubes, one of said members having a nozzle directed to provide suction from one 5 of said tubes and the other member having a nozzle to drive steam through the other tube, and steam delivery means comprising a valve permitting one of said nozzles to be operated independently of the other, substantially as 10 described.

4. In a structure of the nature described, the combination of a head comprising a mouth adapted to be placed in operative relation with one tube of a boiler and having 15 an upwardly directed nozzle, a second mouth piece adapted to be placed in operative relation with a second or companion boiler tube, a steam connection between said heads, a valve in said connection, a handle connected 20 with one of said heads, and an operating device for the valve, whereby the device may be used to clean out one tube by suction and then the valve opened to permit the steam to blow out the companion tube, substantially 25 as described.

5. In a structure of the nature described, the combination of a head comprising a mouth adapted to be placed in operative relation with one tube of a boiler and having 30 an upwardly directed nozzle, a steam delivery tube supplying steam to said head, a

second mouth piece adapted to be placed in operative relation with a second or companion boiler tube, a steam connection between said heads, a valve in said connection, a handle connected with one of said heads, and an operating device for the valve, whereby the device may be used to clean out one tube by suction and then the valve opened to permit the steam to blow out the companion 40 tube, substantially as described.

6. In a structure of the nature described, the combination of a head comprising a mouth adapted to be placed in operative relation with one tube of a boiler and having 45 an upwardly directed nozzle, a tubular handle connected to the said head, a steam delivery tube supplying steam to said head, a second mouth piece adapted to be placed in operative relation with a second or companion boiler tube, a steam connection between said heads, a valve in said connection, a handle connected with one of said heads, and an operating device for the valve, whereby the device may be used to clean out one tube by 50 suction and then the valve opened to permit steam to blow out the companion tube, substantially as described.

In testimony whereof I have signed my name, this 29th day of October, in the year 60 one thousand nine hundred and twenty.

LEONARD M. DAVIS.
